UNITED STATES PATENT OFFICE.

AMOS F. DIXON, OF NEWARK, NEW JERSEY, ASSIGNOR TO WESTERN ELECTRIC COMPANY INCORPORATED, OF NEW YORK, N. Y., A CORPORATION OF NEW YORK.

PRINTING-TELEGRAPH SYSTEM.

1,365,231.

Specification of Letters Patent. Patented Jan. 11, 1921.

Application filed February 14, 1918. Serial No. 217,098.

To all whom it may concern:

Be it known that I, AMOS F. DIXON, a citizen of the United States, residing at Newark, in the county of Essex, State of New Jersey, have invented certain new and useful Improvements in Printing-Telegraph Systems, of which the following is a full, clear, concise, and exact description.

This invention relates to telegraph systems and particularly to printing telegraph systems.

One object of this invention is to provide a printing telegraph system equipped with means for maintaining on the line circuit, which connects the various stations, a low-frequency current for keeping the distributors at the several stations in synchronism, and, furthermore to provide means for selectively superposing high-frequency currents upon the low-frequency current in order to operate selectively the various recorders located at the several stations.

In the printing telegraph system used for describing this invention, sunflower transmitting and receiving distributors are disposed at the several stations along the line circuit. One only of these stations, namely, the terminal station is shown upon the drawing. The revolving brushes for the receiving and the transmitting distributors, when started, are continuously rotated by any suitable motors, as, for example, La Cour motors. One station, and preferably a terminal station, is provided with means for impressing a current of relatively low frequency upon the line circuit in order to operate the various La Cour motors in synchronism with each other. At each station, a filter is provided for connecting the receiving switch to line circuit, and a second filter is provided for connecting a current generator of a relatively high-frequency through a transmitter, which may be a tape transmitter or a keyboard transmitter, to the transmitting sunflower switch, in order that currents of high frequency may be selectively superposed upon the low-frequency current which operates the motors at the various stations. Thus, in a system constructed in accordance with this invention, low-frequency currents are maintained on the line circuit for operating the apparatus at the various stations in synchronism, and high-frequency currents are selectively transmitted to the line circuit for

selectively operating the various recorders.

Although this invention is illustrated by a system utilizing a code having five impulses for differentiating various signals, it is to be understood that this invention is in no way restricted to such a system, and that it is equally applicable to systems utilizing a code having more or less impulses for differentiating the various signals. Moreover, although the drawing shows but a single transmitter connected to one section of a transmitting sunflower switch, and a single recorder connected to one section of a receiving sunflower switch, it is apparent that a number of transmitters and recorders may be connected to other sections of the same sunflower switch in accordance with usual practice. For convenience in illustrating the system, the sections of the various sunflower switches are shown developed.

The single figure in the accompanying drawing is a diagrammatic view of a printing telegraph system constructed in accordance with this invention.

Referring to the accompanying drawing, a terminal station 1 is provided with transmitting apparatus 2, recording apparatus 3, and a suitable motor 4 for operating a receiving and a transmitting sunflower switch.

The transmitting apparatus 2 embodies a section 5 of a suitable transmitting sunflower switch, having contact segments 6 to 10, inclusive, which are successively connected to opposite poles of a divided battery 12, and contact segments 13 to 17, inclusive, which are connected to a transmitter 19. A suitable revolving brush 20, which is connected to a line circuit 21, is provided for bridging the contact segments 6 to 10, inclusive, and the contact segments 13 to 17, inclusive.

The transmitter 19, which may be any suitable tape or keyboard transmitter, embodies a plurality of contact terminals 22 to 26, inclusive, which are connected, respectively, to the contact segments 13 to 17, inclusive, and contact terminals 28 to 32, inclusive, which are selectively engaged by the contact terminals 22 to 26, inclusive.

The contact terminals 28 to 32, inclusive, are connected to ground through a filter embodying an inductive reactance 34 and a capacity reactance 35. The inductive react-

ance .34 is inductively connected to a relatively high-frequency generator 37 by means of a coil 36.

The recording apparatus 3 embodies a section 40 of a sunflower receiving switch, which comprises a common contact segment 41 and a plurality of contact segments 42 to 46, inclusive, which are connected through selecting magnets 47 to 51, inclusive, to ground. The contact segments 42 to 46, inclusive, are connected successively to the contact segment 41 by means of a revolving brush 52.

A receiving filter which embodies an inductive reactance 53 and a capacity reactance 54, is connected between the line circuit 21 and the ground, and a relay 55 is inductively connected to the inductive reactance 53 by means of a coil 56. The relay 55 is provided with an armature 56 which, when operated, connects a battery 57 to the contact segment 41 of the sunflower switch.

The La Cour motor, which is a well-known type of motor, embodies a magnetic disk 60 that is controlled by two or more electromagnets 61 and 62. The two electromagnets 61 and 62 have impulses impressed upon them from a battery 63 that is under the control of a polarized line relay 64.

Assuming the La Cour motor 4 to be in operation, it is apparent that the brush 20 in revolving over the segments of the transmitting sunflower switch, will continuously impress impulses of alternate polarity upon the line circuit 21. These impulses of low frequency from the battery 12 will operate the polarized relay 64 at the home station and the various polarized relays at the several stations along the line circuit for synchronously operating all the La Cour motors. When the motor 4 is in operation, the contact terminals 22 to 26, inclusive, of the transmitter 19 may be selectively operated for impressing high-frequency currents from the generator 37 upon the impulses that are transmitted to the line circuit 21 from battery 12. The high-frequency currents transmitted from the alternating-current generator 37, will selectively operate a recorder at any desired station in a manner to be hereinafter described. It should be noted, however, that the capacity reactance 35 and the inductive reactance 34 prevent short-circuiting of the battery 12 through the segments of the sunflower switch and the transmitter 19.

Assuming the filter at the station 1 to be adjusted to permit the passage of currents of the same frequency as the high-frequency current transmitted from a designated station, it is apparent that the relay 55 will be operated whenever a high-frequency current is received. The selective operation of the relay 55 and the rotation of the distributor

brush 52 connecting the segments 42 to 46 inclusive sequentially with the common distributor ring 42 control the operation of the printing magnets 47 to 51, inclusive. The printing magnets 47 to 51 inclusive may be utilized for suitably operating any well-known printing recorder.

It is obvious that by adjusting the filters at different stations to different frequencies, the system may be made selective in that a station may transmit to one or more stations to the exclusion of the other stations on the same line. The necessary requirement for such a condition is that the filters at the station or stations with which communication is intended to be established, shall be adjusted to admit the passage of currents of the frequency sent out by the transmitting station, and that the filters at all other stations on the line shall be adjusted to exclude currents of that frequency.

Modifications in the system and arrangement and location of parts may be made within the spirit of the scope of this invention, and such modifications are intended to be covered by the appended claims.

What is claimed is:

1. In a telegraph system comprising a transmitting station and a receiving station, a line circuit connecting said stations, current impulse distributing mechanism at each of said stations, means at one of said stations for impressing on the line circuit reversals of current for synchronizing purposes, a plurality of movable contacts, means for selectively operating said contacts to impress on the line circuit, groups of high frequency signaling impulses, all of said impulses being of the same frequency, means at the receiving station responsive to said high frequency signaling impulses and signal responsive devices controlled by the conjoint action of said last mentioned means and said distributing mechanism.

2. In a telegraph system comprising a transmitting station and a receiving station, a line circuit connecting said stations, current impulse distributing mechanism at each of said stations, means at one of said stations for impressing on the line circuit reversals of current for synchronizing purposes, a plurality of stationary contacts, a source of alternating current supply connected to said contacts, a plurality of movable contacts normally connected to one of said current impulse distributors and adapted to be moved into engagement with said stationary contacts for impressing upon the line circuit groups of signaling impulses, all of which are of the same frequency, means at the receiving station responsive to said high frequency signaling impulses, and signal responsive devices controlled by the conjoint action of said last mentioned means and said distributing mechanism.

3. In a telegraph system comprising a transmitting station and a receiving station, a line circuit connecting said stations, a source of synchronizing current at the transmitting station, a single source of alternating signaling current at the transmitting station, a plurality of selectively operable contacts for controlling the application of said signaling current to the line circuit, means 5 for operating said contacts simultaneously, current impulse distributing mechanism for impressing said synchronizing current and said signaling current on the line simultaneously, means at the receiving station responsive only to the synchronizing current, 15 means at the receiving station responsive only to the signaling current, recording mechanism at the receiving station, and current impulse distributing mechanism co-operating with said signaling current responsive means for controlling the operation of said recorded mechanism.
- 10

In witness whereof, I hereunto subscribe my name this 7th day of February, A. D., 1918.

AMOS F. DIXON.
